VENTILATED PLUMBING FIXTURE

Filed June 22, 1934

UNITED STATES PATENT OFFICE

2,041,962

VENTILATED PLUMBING FIXTURE

Thomas J. Robertson, Kansas City, Mo., assignor
of one-half to Paul C. Ford, Kansas City, Mo.

Application June 22, 1934, Serial No. 731,800

6 Claims. (Cl. 4—213)

This invention relates to ventilated plumbing fixtures and more particularly to a ventilated water closet and has for its principal object to provide for withdrawing air from within the toilet bowl and discharging it into the vent stack of the soil pipe to which the fixture is connected, thereby relieving the bowl of foul air that normally escapes into the room wherein the fixture is installed.

10 Other important objects of the invention are to provide a ventilating mechanism built directly into the fixture, to provide means for automatically starting the ventilating mechanism when the fixture is in use, to provide means for sealing the ventilating duct against back flow of gases from the vent stack when the ventilating mechanism is not in operation and to prevent water from leaking into the motor which operates the ventilating fan.

15 20 In accomplishing these and other objects of the invention, I have provided improved details of structure, the preferred form of which is illustrated in the accompanying drawing, wherein:

Fig. 1 is a perspective view of a water closet 25 constructed in accordance with the present invention, a part of the bowl being shown in section to better illustrate its construction and arrangement of ventilating ducts.

Fig. 2 is a plan view of the toilet bowl, part 30 of which is shown in section to illustrate the suction and discharge ducts.

Fig. 3 is a cross sectional view through the motor and fan compartment of the toilet bowl on the line 3—3, Fig. 1.

Fig. 4 is a detail section through the bowl on the line 4—4, Fig. 1, particularly illustrating the water seal for the discharge duct.

Fig. 5 is a detail perspective section through a portion of the bowl and seal illustrating the 40 switch for automatically effecting operation of the fan motor when the toilet is in use.

Referring more in detail to the drawing:

1 designates a water closet including a toilet bowl 2 and a flush tank 3 for containing the 45 water used in flushing the bowl to discharge its contents therefrom as in conventional practice. The bowl 2 includes a hopper portion 4 that is supported on a suitable base 5 and which has a rim 6 extending around the open top thereof to support a toilet seat 7. The toilet seat 7 is provided with hinged brackets 8 having sleeved portions 9 hingedly mounted on a transverse rod 10 that is supported by brackets 11, the brackets being carried on a rear extension 12 of the toilet 50 bowl, as best shown in Fig. 1. The seat may also

be provided with the usual cover 13 which is hinged to the rod 10.

The seat 7 is normally retained in spaced relation with the rim 6 by a spring 14 coiled about the rod 10 and having one end engaging one of the brackets 11 and its other end engaging the sleeve portion 9 of one of the seat hinge members 8.

The spring is wound about the shaft with sufficient tension to support the weight of the seat 10 including the cover 2, but when a person is seated on the toilet, the spring yields to allow the seat 7 to have support on the rim 6 of the bowl for a purpose hereinafter described.

Formed in the base 5 and connected with the upper portion of the bowl is a sump 15 to form a water seal and which terminates in an upwardly and downwardly extending discharge duct 16 having an outlet 17 connected to the customary soil pipe (not shown). Formed integrally with the bowl and projecting downwardly within the sump is a partition 18 cooperating with a lip 19 in the bend 20 of the discharge duct to more effectively form the seal against reverse flow of gases from the soil pipe through the duct and into the bowl. The upper portion of the partition is spaced below the top wall 21 of the bowl to provide a flow channel 22 wherethrough the water in the flush tank is discharged into the bowl, the flow channel being connected with the flush tank through a suitable pipe connection 23 as shown in Fig. 1. Also formed in the bowl and communicating with the outlet of the connection 22 is a secondary flow channel 24 that is connected with a manifold channel 25 extending circumferentially within the rim having an annular outlet 26 for discharging the water down the inner walls of the hopper to maintain the walls of the hopper clean of waste material.

As above pointed out, it is the purpose of the present invention to provide means for withdrawing the foul air from the bowl and discharging the air into the discharge duct at a point below the water seal and to accomplish this purpose, the water flow channel 22 also forms a suction duct which is extended rearwardly within the offset portion of the bowl to communicate with a fan chamber 27 that is formed within the extension of the bowl directly above a motor compartment 28 that is separated from the fan chamber by a horizontal partition 29 as best shown in Fig. 1. The partition is provided with an opening 30 having substantially the same diameter as the fan chamber to permit insertion of a fan 32 therethrough. The opening is nor- 55

mally closed by a plate 33 that is removably secured to the under face of the partition by fastening devices 34.

The motor 35 is suspendingly supported by the 5 plate within the motor compartment and has its armature shaft 36 rotatably mounted in a bearing opening 37 of the plate to directly mount the fan in driving relation with the armature. The opening 37 is sealed about the shaft by a suitable packing ring 38 that is received in a recess in the upper face thereof to prevent moisture which collects in the fan chamber from leaking into the motor compartment.

The fan is preferably of the multi-vane type 15 and has a central air inlet 40 communicating with the flow channel 22 through a port 41 that is formed in the partition 42 forming the top of the fan chamber.

The fan has peripheral discharge communicating 20 with a discharge duct 43 that is formed in the partition 18 and which extends downwardly to terminate in a U-shaped bend 45 having its discharge end located below the surface of the water seal and opening directly into the discharge duct 16. The U-shaped bend thus forms a water seal to prevent back flow of gases through duct 43 and fan chamber into the bowl when the fan is not in operation. When, however, the motor is energized to actuate the 30 fan, the air moved thereby is discharged through the bend 45 displacing the water into the duct 16, but when the fan is stopped, the bend 45 is refilled by water from the toilet bowl to reestablish the seal.

35 In order to effect automatic operation of the motor and the fan driven thereby, the seat 7 operates a switch 46 that is positioned thereunder for actuation when the seat is moved against tension of its spring toward the rim 6 of the bowl. The switch includes a housing 47 having a fixed contact 48 connected with one of the motor leads 49 and a movable contact 50 connected to the current supply wire 51, the other supply wire 52 being directly connected to the 45 other motor lead 53. The movable contact is actuated by a plunger 54 slideable in an opening 55 of the switch housing and projecting therefrom to be engaged by the seat when the seat is moved to depressed condition. Access is had 50 to the motor compartment 28 through an opening 56 in the side wall of the bowl extension. The opening is covered by a plate 57 which is held in place by screws 58 threaded into the extension.

55 When the toilet is in use, the weight of a person on the seat 7 effects closing of the switch to energize the motor to start operation of the fan. The air from the bowl is drawn by the fan through the channels 22, ports 40 and discharged 60 circumferentially of the fan blades into the inlet of the discharge duct 43 which causes displacement of the water in the trap of the duct by reason of pressure of the air moved by the fan. The air flows through the outlet of the discharge 65 duct into the duct 16 from which it is carried away by the vent for the soil pipe (not shown). Any water carried into the fan chamber with the air will be centrifugally discharged from the fan blades and will flow along with the foul air 70 through the discharge duct 43.

When the toilet is flushed, the water seal will overflow into the discharge duct 16, but the water from the flush tank refills the trap 15 to prevent reverse movement of the air when the fan is not 75 in operation.

When the pressure on the seat is released, the spring 44 lifts the seat from engagement with the rim of the bowl to allow release of the plunger 54 to open circuit of the motor and stop operation of the fan.

From the foregoing, it is apparent that I have provided a simple ventilating means wherein foul air is withdrawn from the toilet and discharged into the vent stack of the soil pipe to which the fixture is connected thereby preventing the foul air from escaping into the room wherein the fixture is installed.

It is also apparent that the ventilating mechanism is automatically operated when the toilet is used and that the ventilating ducts are normally 15 sealed against reverse flow of gases when the fan is not in operation by means of water from the water seal of the toilet bowl.

What I claim and desire to secure by Letters Patent is:

1. In a fixture of the character described, a toilet bowl having a discharge duct and a water seal in the bowl for sealing said discharge duct, and means carried by the bowl and having an intake connected with the interior of the bowl 25 for withdrawing air from the bowl and having an outlet connection with the discharge duct at a point within the water seal.

2. In a fixture of the character described, a toilet bowl having a discharge duct and a 30 water seal in the bowl for sealing said discharge duct and having a fan chamber formed as a part of the bowl, said chamber having an inlet connected with the interior of the bowl and an outlet terminating in a reverse bend located below the water seal, a fan in said chamber for withdrawing air from the bowl and discharging the withdrawn air into the discharge side of the water seal, a motor connected with the fan, a circuit for the motor, and a switch in the circuit 40 for effecting actuation of the motor to operate the fan.

3. In a fixture of the character described, a toilet bowl having a discharge duct provided with a water seal for maintaining water in the bowl 45 and having an air duct including a trap portion located within said water seal whereby said trap portion is kept filled with water from the water seal, a fan chamber having an inlet connected with the interior of said bowl above the water 50 seal and an outlet connected with said air duct, a fan in the fan chamber, and means for actuating the fan to withdraw air from the bowl and to discharge said air through said trap portion 55 of the air duct into the discharge duct.

4. In a fixture of the character described, a toilet bowl, a water trap in the bowl and having an inlet connected with the bowl and an outlet, means in the bowl forming an air duct having outlet within the trap on said outlet side, a fan 60 chamber having an inlet connected with the interior of the bowl and an outlet connected with said air duct, a fan in the fan chamber, and means for actuating the fan to withdraw air from the bowl and discharge said air through 65 said trap.

5. In a fixture of the character described, a toilet bowl, a water trap in the bowl and having an inlet connected with the bowl and an outlet, means in the bowl forming an air duct having 70 outlet within a body of water contained in the trap on said outlet side, a fan chamber in the bowl located above the level of water contained in said trap and having an inlet connected with the interior of the bowl and an outlet connected 75

with said air duct, a fan in the fan chamber, and means for actuating the fan to withdraw air from the bowl and discharge said air through said trap.

5. 6. In a fixture of the character described, a toilet bowl having a depending partition to form a U-shaped water seal in the bottom of the bowl, a fan connected with the bowl and having an inlet connected with the interior of the bowl at

a point above the water seal and having an outlet connected with a discharge duct extending in said partition and terminating in a reverse bend below the water seal, and means for actuating the fan to withdraw odors from the interior of the bowl and for discharging the odors through said reverse bend at substantially the level of the water seal.

THOMAS J. ROBERTSON.
